Goopreen Silicone Caulking tool, 5 in 1, AMAZON.com, Apr. 12, 2024.*

* cited by examiner

Primary Examiner — Philip S Hyder(74) *Attorney, Agent, or Firm* — Ricky Lam(57) **CLAIM**

The ornamental design for a caulking tool, as shown and described.

DESCRIPTION

FIG. 1 is a front perspective view of a caulking tool, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a perspective view of the caulking tool, wherein its components are shown in alternate positions.

The broken lines in the drawings illustrate the portions of the caulking tool, which form no part of the claimed design.
